UNITED STATES PATENT OFFICE.

EVERETT H. BARNEY, OF SPRINGFIELD, MASSACHUSETTS.

SKATE.

SPECIFICATION forming part of Letters Patent No. 235,492, dated December 14, 1880.

Application filed April 29, 1876.

To all whom it may concern:

Be it known that I, EVERETT H. BARNEY, of Springfield, in the State of Massachusetts, have invented a new and useful Improvement 5 in Skates; and I do hereby declare that the following is a full, clear, and exact description thereof, reference being had to the accompanying drawings, making a part of this specification, and to the letters of reference marked 10 thereon.

Referring to the drawings, Figure 1 is a side elevation of my improved skate. Fig. 2 is a plan view of the top edge of the runner and the top of the standards, with the sole and heel 15 plates removed. Fig. 3 is a side elevation of the toe of the runner and the forward standard, with the sole-plate removed. Fig. 4 is a side elevation of the heel of the skate and rear standards, with the heel-plate removed. Fig. 20 5 is a view, in vertical sections, through the rear standards, on the line xx , Fig. 1.

Like letters and figures refer to the same parts in the different views.

My invention relates to such skates as are 25 made wholly of metal; and my improved skate consists of a cast-iron runner and standards cast in one piece, with the runner cast thickest along its lower edge, forming ribs on both sides of the web, and a portion of the standards being cast with double vertical strengthening- 30 ribs united at their upper ends to form a broad support on the top of said standards for the sole and heel plates, which are made of malleable iron and riveted to the standards above 35 mentioned. On the under side of the said sole-plate and heel-plate are secured the clamps worked by screws to secure the skate to the boot.

In the drawings, A represents the sole-plate 40 of the skate, and B the heel-plate, both cast of malleable iron, with the downwardly-projecting pieces, a , cast thereupon standing at right angles to the under face of said plates, and afterward being bent inwardly toward 45 each other, so as to form supports for the clamps b , which slide between them. The said clamps b are made to grasp the sole and heel of the boot by screwing up the screws m , which pass through the ears n of said clamps.

50 Two rear standards, 3 and 4, are cast on runner D, leaving an intervening opening, I, between them.

The ears n of the heel-clamps b are free to approach each other under the heel-plate, working through opening I by screw m . 55

D is the runner of the skate. 1 2 3 are the standards thereof, and E is a strengthening-rib on both sides of the web, running from the heel of the runner D up to and across the top of standard 4, where it increases in lateral 60 dimension, thence around the edge of opening I, and thence up to and across the top of standard 3, where it increases in lateral dimension, and from the latter along the top of edge-runner D, and up the rear edge of standard 2 to 65 the under side of the sole-plate. From the forward edge of standard 2 up against the sole-plate a strengthening-rib F commences, following the top edge of runner D to the rear edge of standard 1, and upward to the sole- 70 plate, where it increases in lateral dimension. Said rib recommences in the same form under the sole-plate just described on the front edge of standard 1, and runs down the said front edge to the toe of the runner. The strength- 75ening-rib E, as it crosses the tops of the standards 3 and 4, increases in lateral dimension, having a bracket form, as shown at d , and forms broader supports for the heel-plates, and, following the front and rear edges of standards 3 and 4, it forms strong vertical supports for said standards. Rib F adds strength to 80 that portion of the runner immediately under the sole-plate, and, passing up the rear edge of standard 1, increases in lateral dimension 85 at its junction with the sole-plate. Thus on the top of standard 1 is formed a broad support for the forward end of the sole-plate, and the vertical portions of rib F on the front and rear edges of standards 1 give to that stand- 90 ard all required strength.

Riveting-studs are cast on the tops of the standards, as partly shown in Figs. 3 and 4, by means of which the sole and heel plates are riveted thereto. 95

The lateral extension in bracket form of the strengthening-ribs, which pass horizontally across the tops of the standards, forms broad-faced supports for the sole and heel plates.

I cast my skate-runner thickest along the 100 bottom edge, and reduce the thickness of the runner above the said thick portion, so that the skate-runner may have its bottom edge and two opposite sides conveniently ground or other-

wise finished, for the purpose of forming the requisite sharp longitudinal edges on the bottom of the runner, without grinding or finishing the sides of the runner any higher than may be required to produce the requisite finish on the side of the runner immediately above said sharp edges. Also, by casting the bottom edge of the runner thicker for a short distance above its bottom edge, I provide a definite finish-line on the side of the runner, leaving the portion above said finish-line untouched by the finishing or grinding tool.

I do not claim any particular form for the ribbed upper edge of the runner of this skate, as it is obvious that that is not essential.

Having thus described my invention, what I claim as new, and desire to secure by Letters Patent, is—

1. The combination of the sole-plate A, clamps *b*, screw *m*, hook-supports *a*, standard 1, with its vertical ribs F, having lateral extensions *d*, of a bracket form, and standards 2, substantially as and for the purpose set forth.

2. The runner-standard of a skate cast with double vertical strengthening-ribs, united at their upper ends by a lateral extension, *d*, of the rib, having a bracket form, for the support of the sole and heel plate, the said ribs increasing in lateral dimension as they approach the said sole or heel plates, substantially as and for the purpose set forth.

3. The combination of the heel-plate B, standards 3 and 4, with their double vertical ribs E, and the lateral extension *d* of the rib, having a bracket form surrounding the end 35 thereof under the sole-plate, clamps *b*, screw *m*, and hook-supports *a*, substantially as and for the purpose set forth.

4. The runner of a cast-iron skate, constructed with a web and with a rib cast on each side 40 thereof, along its bottom edge, substantially as set forth.

EVERETT H. BARNEY.
